Floyd J. Hurst, Gainesville, Tex.

Application November 22, 1954, Serial No. 33,178

Term of patent 14 years

(Cl. D87—3)

To all whom it may concern:

Be it known that I, Floyd J. Hurst, a citizen of the United States, residing at Gainesville, Cooke County, Texas, have invented a new, original, and ornamental Design for a Lady's Handbag or Similar Article, of which the following is a specification, reference being had to the accompanying drawing, forming a part hereof.

Figure 1 is a front perspective view of one side of a lady's handbag or similar article showing my new design.

I claim:

The ornamental design for a lady's handbag or similar article, substantially as shown.
